UNITED STATES PATENT OFFICE.

PIERRE ALBERT RAYMOND, OF GRENOBLE, FRANCE.

SHOE-FASTENING.

SPECIFICATION forming part of Letters Patent No. 449,273, dated March 31, 1891.

Application filed August 11, 1890. Serial No. 361,669. (No model.) Patented in France June 28, 1890, No. 206,681, and in England July 3, 1890, No. 10,315.

To all whom it may concern:

Be it known that I, PIERRE ALBERT RAYMOND, a citizen of the French Republic, residing at Grenoble, France, have invented 5 certain Improvements in Fastenings for Shoes, Corsets, and the Like, (for which a patent has been granted in Great Britain, No. 10,315, dated July 3, 1890, and in France, No. 206,681, dated June 28, 1890,) of which the following 10 is a specification.

My invention relates to that class of fastening devices for shoes, corsets, gloves, and the like wherein the two parts of the article to be brought and secured together are provided 15 with retainers for a lacing-cord, said retainers being in the nature of hooks, eyes, eyelets, &c.; and the object of my invention is in part to improve the construction of the retainers for the lacing-cord and in part to provide 20 a simple and effective means for securing said retainers in the material, whereby the opening in the material will be closed by the devices employed for securing the retainers therein, and the retainer will be given a 25 broad base and will project very slightly from the face of the material.

My invention will be fully described hereinafter, and its novel features carefully defined in the claims.

30 In the accompanying drawings, which serve to illustrate my invention, Figures 1 and 2 are respectively a side and front elevation of a retainer having the form of a hook constructed and set in the material in accordance 35 with my invention. In these views the securing-eyelet and cap-plate are represented in section in order to better illustrate the form and construction of the retainer. Figs. 3 and 4 are respectively a side elevation and plan 40 view of the retainer detached. Figs. 5 and 6 are respectively a transverse section and plan of the cap-plate detached. Figs. 7 and 8 are respectively a transverse section and plan of a slight modification in the cap-plate that will 45 be hereinafter described. Figs. 9 to 15 illustrate an embodiment of my invention wherein the retainer for the lacing-cord has the form of a closed hook or eye. Figs. 9, 10, 11, 12, and 15 correspond, respectively, to Figs. 3, 4, 50 5, 6, and 1. Figs. 13 and 14 are respectively

a transverse section and plan of the eyelet employed for binding the parts of the fastening together and to the material in which they are set. Fig. 16 is a view showing my improved fasteners applied to a shoe.

X represents the material in which the fastenings are set, and C is an eyelet, which may be of the usual kind, adapted to be set in a hole punched in the material X.

55 Referring to Figs. 1 to 8, inclusive, A is a 60 retainer for the lacing-cord in the form of a hook, and B the cap-plate. This latter is in the form of a shallow cup, and its upturned rim is bent inward to form a flange b. The retainer A is formed of wire doubled on itself 65 and bent to shape and its extremities turned outward in opposite directions to form feet a, which may be slightly spread or flattened, as seen in Fig. 4.

In assembling the parts of the device and 70 setting it in the fabric a hole is punched in the material and the eyelet C pushed through from the outside until its primary outer flange c^x rests on the outer face of the material. The base of the retainer A is now inserted in 75 the cap-plate B, its feet a taking under the inturned flange b thereon. The retainer A is now passed through the eyelet C from the back until the cap-plate houses the projecting end or flange of the eyelet. The parts 80 are now forcibly pressed together until the material X is tightly clamped between the cap-plate and the outer flange of the eyelet. The other flange c^x of the eyelet will now be found to be expanded and turned outward 85 within the hollow of the cap-plate, and the feet a of the retainer A clamped firmly between it and the crown of the cap-plate.

To steady the base of the retainer, I prefer to provide the cap-plate B with keepers c c 90 on its inner face to embrace the feet a, as seen in Fig. 2. These keepers may, however, be formed on a separate plate, which will be placed in the hollow of the cap-plate. Such a plate F is seen in Figs. 7 and 8.

95 Where the retainer for the lacing-cord has the form of an eye or bail, through which said cord must be threaded, the construction of the eyelet and cap-plate will be substantially the same as has been described. This 100

form of the fastening is illustrated in Figs. 9, 10, 11, 12, and 15.

The retainer D is of a U shape, provided with spread or flattened feet d, which take under the inturned flange e on the cap-plate E. This cap-plate has a conical projection on its face, which serves as a keeper to steady the feet of the retainer D.

The assembling of the parts and the setting 10 in the material X is the same as before described.

The manner of securing the parts together by means of a lacing-cord, when provided with fastenings constructed according to my 15 invention, is illustrated in Fig. 16, wherein a shoe is shown provided at the lower part of the slit with cord-retainers in the form of eyes and at the upper part with retainers in the form of hooks.

20 My fastening device has several advantages over the old varieties of fastenings, among which may be noted: First, the opening provided for the attachment of the fastening is bound by the eyelet and tightly closed by the 25 cap-plate, thereby excluding water when the fastening is employed on shoes; second, the cord-retainer projects very slightly above the surface of the material, and its attachment being at the inner face of the material the 30 space within the eyelet is utilized to afford room for the lacing-cord, (therefore the strain of the cord is tangential to the material and does not tend to cant or tilt the retainer in such a manner as to cause the wearer pain,) 35 and, third, the cord-retainer being made of half round or oval drawn wire, the lacing-cord encounters no sharp angles, and consequently is not chafed or worn.

Having thus described my invention, I claim—

1. In a fastening device for shoes and the like, the combination, with an eyelet set in the material and a flanged cap-plate which embraces the inner clinched end or flange of said eyelet, of a retainer for the lacing-cord, 45 which retainer projects through the eyelet and has a base which is clamped between the cap-plate and the inner flange of the eyelet.

2. In a fastening device for shoes and the like, the combination, with the retainer for the 50 lacing-cord, provided with feet, as described, of the eyelet set in the material, and the cap-plate provided with a keeper for the feet of the retainer, said retainer projecting outwardly through the eyelet and having its feet 55 clamped between the said cap-plate and the inner flange of the eyelet, whereby the retainer is secured to the eyelet and through it to the material.

3. In a fastening device for shoes and the 60 like, the combination, with a hook to form a retainer for the lacing-cord, provided with feet, as described, of the eyelet set in the material, and a cap-plate provided with a keeper for the feet on the hook, said cap-plate embracing said fingers and the lower flange of the eyelet, whereby said hook is secured to the eyelet and therethrough to the material. 65

In witness whereof I have hereunto signed my name in the presence of two subscribing 70 witnesses.

PIERRE ALBERT RAYMOND.
